(57) **CLAIM**

The ornamental design for a closure for containers, as shown and described.

DESCRIPTION

FIG. 1.1 a top perspective view showing my new design;

FIG. 1.2 is a bottom perspective view thereof;

FIG. 1.3 is a top view thereof;

FIG. 1.4 is a bottom view thereof;

FIG. 1.5 is a left side view thereof; and

FIG. 1.6 is a right side view thereof.

The broken lines depict portions of the closure for containers that form no part of the claimed design.
